RECORD

Richard W. Sears, II, Evanston, Ill.

Application November 5, 1941, Serial No. 417,893

10 Claims. (Cl. 274—42)

This invention relates to records for recording sound, from which sound reproductions may be made.

An important object of the present invention is the provision of a new and improved type of record, whereby there may be embodied within the record, during the manufacture thereof, one or more means for permitting or allowing the record to be autographed by the author or recorder.

Another important object of the invention is the provision of a record which is provided with an underlying protective paper or coating adapted to receive the imprint of the author's signature or symbol, and when signed or autographed leave some permanent identification or record as to the signing or autographing of the record.

A further object is to provide a record having a recording surface upon which the sound waves may be cut or embossed and a lower or underlying surface adapted to receive the author's signature or symbol which is incapable of being removed without leaving some telltale evidence.

A still further object of the invention is to provide a disk-like record having an exterior surface upon which sound waves may be cut or embossed, there being a cut-out provided in the outer surface to allow the author of the record to sign the record whereby there is provided a lower surface of safety paper to receive the imprint of the signature and leave some evidence to indicate that the signature had been tampered with if such were the fact.

Still another object of the invention is to provide a disk-like record having embodied therein, preferably during the manufacture thereof, a sheet of transfer material such as carbon paper which is adapted to show the signature or other indicia marked upon the surface of the record.

Still another object of the invention is the provision of means embodied within the upper and lower surfaces of the record to permit easy mutilation and destruction of the record if and when desired.

Still another object of the invention is to provide a record which is provided with a surface adapted to have sound waves cut, embossed or otherwise provided therein, which is provided with a lower surface beneath the sound recording surface to receive the signature or other indicia of the author or remarks or instructions, which is provided with means whereby a writing on the record surface by a stylus pencil or otherwise will be visible, which is provided with means whereby a duplicate of the signature may be retained

by the signer so that a comparison may be made with the signature on the record itself to determine its genuineness, which is provided with means for permitting removal but preventing replacement of the same or another transfer sheet, which is provided with means to permit a signature to be applied on the face of the record below its normal recording surface, and which is provided with means within the body of the record to permit quick and easy mutilation or destruction of the record.

A still further object of the invention resides in the provision of a record which is provided with means whereby certain information or data may be transmitted with the assurance that the recipient will receive the original genuine data carried by the record with undeniable proof that the recorded data is the authorship of the original author or recorder, there being new and improved means to provide certain indicia, symbols or signature means to indicate the genuine authorship.

Numerous other objects and advantages will be apparent throughout the progress of the following specification.

The accompanying drawings illustrate a selected embodiment of the invention and the views therein are as follows:

Fig. 1 is a detail plan view of a record and embodying the invention.

Fig. 2 is a detail sectional view on the line 2—2 of Fig. 1.

Fig. 3 is a detail sectional view on the line 3—3 of Fig. 1.

Fig. 4 is a detail perspective view of the improved record showing the transfer sheet removed therefrom and the manner in which the record may be mutilated by the manipulation of an imbedded ribbon.

Fig. 5 is a detail sectional view taken radially of the record on the line 5—5 of Fig. 4, showing the transfer means in position.

Fig. 6 is a view similar to Fig. 5 but showing the transfer means removed therefrom.

Fig. 7 is a detail sectional view of the line 7—7 of Fig. 4.

The particular record herein shown for the purpose of illustrating the invention may comprise an upper or top recording surface 8, a lower or bottom surface 9 which may also be a recording surface like the upper recording surface 8, and an intermediate or central section 10 to which the surfaces 8 and 9 are secured or otherwise attached.

The upper recording surface 8 of the record,

as well as the bottom surface 9 thereof, if the record is a double disk record, that is, a disk record having a recording surface on each of two opposite sides, is adapted to be made of any suitable material such as plastic, metal or other material in which proper sound waves may be cut or formed. The upper surface 8, or in the case of a double disk record, also the lower surface 9 may be provided with a cut out portion 11 to expose the intermediate or central section 10. The intermediate or central section 10 may be material 12 having safety printing 13 on each surface so that the author of the recordation may sign the record to indicate the authorship thereof in the same manner in which he signs a letter. The safety paper 12 is provided so that any tampering with the signature will be readily and instantly discernible. Instead of having a single ply of double material 12 having a safety surface 13 on each side thereof, the material 12 may be separate upper and lower sheets as indicated at 14 and 15, the outer surface of each being provided with the safety printing 13.

In cases where the opposed single faced material 12 is provided the intermediate filler or section 10 may include a filler spacing member 16. It is immaterial whether both the faces 8 and 9 are surfaces upon which sound waves may be cut or whether the record is single faced. It is also immaterial whether the central section 10 comprises a single sheet having double faced safety printing thereon or if there be separate sheets 14 and 15 mounted upon a central filler 16. The invention contemplates the use of a safety material upon which the author may place his signature whether it be a single or double disk record.

The invention further contemplates the provision of additional means for receiving and permanently associating a signature, autograph, indicia, or other symbol of the author with the record. This latter embodiment may comprise the provision of one or more recesses 17 provided intermediate the upper and lower surfaces 8 and 9. If the record is a single disk record or a double disk record using the single sheet of double-faced safety material 12, then perhaps only one recess 17 is required, but where the record is of the type embodying a filler 10 having the central filler section 16 and the upper and lower sheets 14 and 15, spaced upper and lower recesses 17, Fig. 4, are preferably provided. The recess or recesses 17 are adapted to receive a sheet of transfer material 18 which may be carbon paper, either single or double-faced, depending upon the construction of the body of the record. The transfer member 18 is adapted to be incorporated in the body of the record during the manufacture thereof, and is positioned so as to provide a pull out tab 19. After the record has been completed, the author may sign his name as indicated at 20, Fig. 4, by exerting pressure on the upper face of the record, it being made of flexible material, whereby the signature is transferred to either the safety paper, the under side of the recording surface or both and, if the recording surface 8 or 9 is made of transparent or translucent material, can be readily seen, when the transfer member 18 is removed. The signature will also appear on the transfer member as well as being permanently applied to the body of the record. It will be readily understood that the application of the signature may be made preliminary to the sound recording. In cases where it is desired to transfer the signa-

ture or the like to both the backing and the under surface of the recording member, the transfer sheet may be double carbon paper that is capable of transferring from both sides and one or more sheets 18 may be radially inserted in slots 17 properly positioned in the body of the record. In cases where the record is made of a smooth, transparent material such as a plastic, and it is relatively impossible to transfer the signature by the carbon process to the under surface of the members 8 or 9, then a thin sheet of tissue paper 21 may be applied on the top of the carbon paper so that the signature can be seen through the transparent material, the writing in such cases being preferably done with a relatively blunt object such as a stylus. In the latter case the tissue paper will be left intact within the body of the record and the carbon paper may be removed if desired or the carbon paper may be left in position in contact with the tissue paper so that the signature will be plainly visible through the transparent or translucent recording surface. The filler 10 whether comprising a single sheet of material 12 or whether including the parts 14, 15 and 16 may be provided with a tongue 22 formed therein so that should the transfer sheet 18 be removed it will be impossible to reinsert it again.

It is often desirable that some means be provided to indicate on the record that the purpose for which it was intended has been satisfied, much in the same manner in which a stenographer checks off her sheets of shorthand notes, and to facilitate such an indication, as well as to assist in mutilating or destroying the record, a ribbon of wire 23 or other suitable material may be incorporated in the body of the record. This ribbon 23 may include an outwardly extending tab 24 so that it may be easily grasped by the hand, as indicated in Fig. 4, and pulled so as to break the recording surface. As many of these ribbons 23 as required may be inserted in the body of the record. These ribbons 23 may extend from the center outwardly and radially or they may extend completely across the entire record as indicated in Fig. 4.

The transfer sheet 18 may also be used for the purpose of providing indications 25 or other symbols to show the beginning and end of a message or a certain type of recordation.

A conventional circular label 26 may be applied to the surface 8 and also the lower surface 9 if desired for advertising purposes, instructions or other data or material in the usual manner.

The invention provides a record of the conventional disk type, whether single or double surfaced, but contemplates the use of means for permitting the autographing or signing of the record by the author in the same manner in which a conventional letter is signed by the writer. The invention also includes means to definitely indicate the genuineness of the authorship and to prevent forgery or to give some telltale evidence should the signature be tampered with. Moreover, the invention includes an element which is adaptable to be withdrawn, but which is prevented from being replaced and in this connection the invention has some similarity to applicant's co-pending application, Serial No. 405,965 filed August 8, 1941, upon which Letters Patent No. 2,316,815 issued on April 20, 1943. However, this co-pending application does not include the specific elements of construction, the manner of embodying the elements, nor the means for effecting the mutilation of the record.

Changes may be made in the form, construction and arrangement of the parts without departing from the spirit of the invention or sacrificing any of its advantages and the right is hereby reserved to make all such changes as fairly fall within the scope of the following claims.

The invention is hereby claimed as follows:

1. A disk record having a sound recording surface on each of its opposed sides, a filler intermediate the opposed surfaces, said filler having a depressed portion on each side thereof, a layer of safety paper adjacent each side of the filler and conforming therewith, said depressed portions of the filler providing a space between each recording surface and the safety paper, and a removable transfer sheet arranged in each space to imprint on the adjacent safety paper an inscription impressed on a recording surface by the use of a stylus.

2. A disk record having a sound recording surface on each of its opposed sides, a filler intermediate the opposed surfaces, said filler having a depressed portion on each side thereof, a layer of safety paper adjacent each side of the filler and conforming therewith, said depressed portions of the filler providing a space between each recording surface and the safety paper, and a removable transfer sheet arranged in each space to imprint on the adjacent safety paper an inscription impressed on a recording surface by the use of a stylus, each recording surface having a cut-out portion whereby an inscription may be made directly on the safety paper.

3. A disc record comprising a disc having a sound recording surface portion of flexible material and a backing portion integrally united with said first mentioned portion for a major part of the adjacent area of said surface portion and separated therefrom for the remainder of said area so as to provide a recess for the reception of a transfer means, said backing portion having a surface for receiving an inscription by transfer.

4. A disc record comprising a disc having a transparent sound recording surface portion of flexible material and a backing portion integrally united with said first mentioned portion for a major part of the adjacent area of said surface portion and separated therefrom for the remainder of said area so as to provide a recess for the reception of a transfer means, said backing portion having a surface for receiving an inscription by transfer.

5. A disc record comprising a unitary disc having a sound recording surface portion of flexible material and a safety paper backing portion integrally united with said first mentioned portion for a major part of the adjacent area of said surface portion and separated therefrom for the remainder of said area so as to provide a recess for the reception of a transfer means.

6. A disc record comprising a disc having a sound recording surface portion of flexible material and a backing portion capable of receiving an impression by transfer integrally united with said first mentioned portion for a major part of the adjacent area of said surface portion and separated therefrom for the remainder of said area so as to provide a recess for the reception of a transfer means.

7. A disc record comprising a disc having a sound recording surface portion of flexible material and a backing portion integrally united with said first mentioned portion for a major part of the adjacent area of said surface portion and separated therefrom for the remainder of said area so as to provide a recess for the reception of a transfer sheet, and a transfer sheet removably received in said recess, said backing portion having a surface for receiving an inscription by transfer, the parts being conformed and arranged whereby upon indicia being impressed on the recording surface portion said indicia will be transferred to the said surface of the backing portion.

10 8. A disc record comprising a disc having a sound recording portion of flexible material and a backing portion capable of receiving an impression by transfer integrally united with said first mentioned portion for a major part of the adjacent area of said surface portion and separated therefrom for the remainder of said area so as to provide a recess for the reception of a transfer means, and a radially disposed ribbon embedded in the record adjacent said first mentioned portion, said ribbon having a portion projecting beyond the edge of the record to provide a pulling tab, whereby the recording surface may be mutilated by exerting a pull on the ribbon.

20 9. A disc record comprising a disc having a sound recording surface portion of flexible material and a cut away portion therein arranged in spaced relation with the axis of said disc, a safety paper backing portion integrally united with said surface portion for a major part of the adjacent area of said surface portion and separated from said surface portion for the remainder of said area so as to provide a recess for the reception of a transfer means, and transfer means removably received in said recess, the parts being conformed and arranged whereby an inscription may be applied through said opening directly on the safety paper and upon indicia being impressed on the surface portion said indicia will be transferred to the safety paper backing portion.

25 10. A disc record having a sound recording surface on each of its opposed sides, a filler intermediate the opposed surfaces, said filler having a depressed portion on each side thereof, a layer of safety paper adjacent each side of the filler and conforming therewith, said depressed portions of the filler providing a space between each playing surface and the safety paper, and a removable transfer sheet arranged in each of said spaces to imprint on the adjacent safety paper an inscription impressed on a recording surface by the use of a stylus or other instrument, there being in each recording surface an opening whereby a surface of the safety paper will be exposed to receive a signature, and a radially disposed ribbon embedded in the record between each recording surface and the adjacent safety paper whereby the recording surface may be mutilated by exerting a pull on the ribbon, a portion of the ribbon projecting beyond the edge of the record to provide a pulling tab.

RICHARD W. SEARS, II.
